CECIL E. DAWSON, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

FLEXIBLE CONTAINER AND MEANS FOR FACILITATING THE FILLING THEREOF.

Application filed April 26, 1923. Serial No. 634,827.

This invention relates to improvements in dispensing devices and more particularly to flexible paper containers of an inexpensive character intended for but a single service, and adapted to contain ice cream, water ices, and the like associated with means for temporarily reinforcing the mouth portion of the container to facilitate the filling of the latter.

It has become a well known practice to dispense refreshments such as ice cream and ices in open or relatively exposed places such as ball parks, fairs, and on the street, where the user cannot or perhaps has no inclination to be particular concerning the condition of his hands. It is in this desirable field of service, more especially, to which my invention relates, although it is not in any sense limited to such field. It is my aim to provide a container that will be as cheap as possible in its construction and manufacture, but thoroughly efficient in protecting the contents being dispensed from contact with the hands, and while sufficiently strong to support the contents without leakage, will at the same time be highly flexible to permit ready changing of its shape so that the mouth of the container may be contoured as desired to the mouth of the user and thus facilitate emptying of the contents from the container.

It is becoming a necessity to enact laws compelling sanitary dispensing of food products when sold on the streets as in the densely populated sections of large cities as is known to exist, for instance, among the poor of the larger cities, and where children, as well as others, desire to purchase and immediately eat some little refreshment such as herein contemplated. They usually have but few pennies to spend and it will be clear that the provision of a sanitary dispenser to meet the ends to which I have just alluded, must in themselves cost a very insignificant amount. They must be made in great quantities, with great simplicity, but always with regard to efficiency, and here the more serious consideration resides in the formation of the bottom of the container which will normally perform its supporting and sealing functions while at the same time permitting collapse, or crushing as the hands of the user presses the con-

tainer from without to expel the contents from within.

In producing a container in keeping with the objects herein expressed, a good paper impervious to a suitable degree may be utilized, but the same of necessity must be of very thin character, and light weight to minimize the cost, and to provide the high degree of flexibility enabling its proper manipulation in the hands of the user. However, this high degree of flexibility is such as to be incapable of withstanding the application of extraneous objects such as a spoon or ladle in filling the container. It will be recalled that in dispensing ice cream or water ice, the salesman customarily dips his spoon into the freezer and then turns the same over with its contents to drop the latter into the container, wiping the spoon across the object of the container to insure complete liberation of the spoon contents. While this operation is effective when the spoon or equivalent implement engages a container having a hard or stiff edge such as in a porcelain, composite, or metal dish, the operation would be immediately destructive if followed in the case of my flexible container. Therefore, I have provided the reinforcing implement hereinbefore mentioned, the same being broadly in the nature of a ring-like band or equivalent member, formed of appropriate material, conveniently of metal, adapted to be removably inserted preferably into the mouth of the paper container, or, in instances, exteriorly thereof, to hold the container in truly open condition while being filled, and affording a relatively rigid edge across which the spoon or implement may be drawn in freeing the contents of the same, desirable in satisfying the purchaser of the full measure of his purchase.

The invention still further embraces a removable attachment such as I have last indicated provided with a handle or gripping portion to be grasped by the salesman or one serving the cream or ice so that his hands may not touch or contaminate the matter being dispensed; and the same underlying thought may be found embodied in the provision of another form of attachment in the nature of the fixture relatively permanently supported.

From the foregoing, it will be apparent to persons skilled in the art to which the present invention appertains, that the same may find practical embodiment in various forms and devices, as may be embraced within the scope of the hereto appended claims, but for the sake of imparting a better understanding of the invention, I have illustrated in the accompanying drawings the two preferred embodiments thereof, with additional illustrations of changes and illustrations in the construction thereof, all as will be clear from the following description when read in connection with the drawings.

In the drawings:—

Figure 1 is a perspective view of the paper container;

Figure 2 is a similar view, parts being broken away showing the application of the container to the reinforcing means adapted to temporarily strengthen the mouth of the container during the filling operation;

Figure 3 is a vertical sectional view through the container and reinforcing device;

Figures 4, 5, 6 and 7 are fragmentary sectional views illustrating various ways of forming the upper or exposed edge of the reinforced device;

Figure 8 is a perspective view of the modified form of reinforcing device adapted for relative permanent fastening to a supporting wall, counter, and cart, or like conveyor; and

Figure 9 is a perspective view of the container in its squeezed or crushed condition and flattened at the mouth for engagement with the lips of the user.

Referring more particularly to the drawings wherein like reference characters designate the same parts in the several views, 2 represents the body of a paper container of such an impervious nature as to withstand the single service for which it is intended, and formed of a single piece of thin and correspondingly highly flexible material, having its edges cemented together as at 3, the body preferably tapering in the downward direction, and of circular cross section. Owing to the flexibility of the body its capability of resisting external pressure is practically nil and in fact the character of the body may be defined as practically incapable in itself of maintaining its intended circular cross section, as best suggested in Figure 1. This is mentioned to emphasize the degree of flexibility that the container is intended to possess.

The bottom of the container is represented at 4, the same being of circular form and possessing an upturned flange 5 cemented to the interior surface of the body so that the bottom will be slightly above the lower edge of the container so that if the container is temporarily rested on any object, the same

may avoid any slight elevations or obstructions. This bottom is of the same highly flexible thin material stiffened as an inherent result of its circular contour with the upstanding flange, constituting the same an adequate support for the container contents. The arrangement of the upturned flange is such as to have the same conform in its application to the container body evenly to the interior surface of the body and a strong cement is used in uniting the flange and body so that the holding capacity of the cemented portions will be so strong that they will withstand more than the capacity of the paper stock of the body and bottom in tearing or puncturing strains and pressures. In this way I am sure that the container may be squeezed and crushed in the hand so that all of the contents may be expelled, after the fashion, crudely speaking, of the manipulation of a flexible container for tooth paste and similar articles found on the market. The idea is illustrated in Figure 9 where the container is shown partially squeezed at the bottom, the latter crushing and bending up with great facility for the purpose, and the mouth of the container flattened to be introduced into the mouth of the user, it being appreciated that the lips of the latter will find a pleasing, smooth and clean engagement with the outer surface of the paper in freeing the contents from the container.

Now, as to the filling of the container, it is readily seen that it would be most difficult to use a spoon or equivalent implement in delivering cream or ice to be dispensed directly into the paper container, and to create an ease and nicety in this dispensing operation, I provide a metal ring or band 6 of a size complementary to the size of the mouth of the container and tapering in accordance with the taper of the body adapted to be introduced into the mouth of the body as shown. This will hold the container open, it being understood that the container will be held to the band by the fingers of the server, and the band will give a stiff or rigid edge on which to scrape the spoon. Preferably the band has its upper edge flanged as at 7 so as to rest upon the upper edge of the body, this flange being shown of differing shapes, subject to the will of the user as clearly understood from Figures 5, 6 and 7 wherein the modified flanges are depicted at 8, 9 and 10, respectively, Figure 4 at 11, illustrating the device with a relatively sharp edge or an edge devoid of any flange whatever.

A handle 12 is formed to be carried by the reinforcing ring to assist in the introduction and withdrawal of the latter from the paper container, it having been found that the ring may be readily slipped out from the container contents by slipping away from

the latter. The handle renders the device sanitary in every particular in that the ring or band need not be touched by possibly soiled fingers.

5 In Figure 8 the ring or band, here represented at 13, in lieu of the handle of the first illustrated embodiment of the invention, has an angular bracket 14 projected therefrom to be detachably secured as at 15
10 in any convenient position. In the use of this permanent fixture, so to speak, the paper containers may be individually removed from their sanitary cartons or other casing and slipped by the hand over the
15 ring or band and there held by a slight pressure of the thumb and forefinger until filled from the spoon or dipper manipulated by the other hand of the server and emptied by the engagement of the same with the rim or
20 edge of the holder as herein clearly set forth.

Up to the present I have referred to the preferable introduction of the reinforcing ring or band into the container, but there
25 will be instances where it will be of advantage, and it is altogether practical, to slip the container into the ring so that the latter will perform its reinforcing function exteriorly of the container as distinguished from
30 interiorly thereof, all of which will be obvious. In the latter use, the container on the one hand may rest upon a table or flat surface while being filled, or, on the other hand, may be supported by simply resting in the
35 palm of the hand of the server.

I do not desire to be misled in my reference to ring or band to imply that the same must be of a continuous formation through-

out because it will be instantly seen that a ring provided with dependent fingers or 40 openwork portion, or other spaced projections may serve quite efficiently although the band would be preferable from the standpoint of sanitation in being smooth and readily cleaned and offering no recesses, 45 crevices, or perforations for the accumulation of germs or dirt.

Having thus described my invention, what I claim is:

1. A ring adapted to extend into the 50 mouth of a flexible walled receptacle a comparatively short distance to reinforce the same when filling the receptacle, the open filling end of the ring being substantially coterminal with the open end of the receptacle so that the receptacle charge may be dropped directly into the receptacle on scraping the charge from a charge carrying implement against the open end of the filling ring. 60

2. A ring adapted to extend into the mouth of a flexible walled receptacle a comparatively short distance to reinforce the same when filling the receptacle, the open filling end of the ring being substantially 65 coterminal with the open end of the receptacle so that the receptacle charge may be dropped directly into the receptacle on scraping the charge from a charge carrying implement against the open end of the filling ring, and a narrow flange on the filling end of the ring. 70

In testimony whereof I hereunto affix my signature.

CECIL F. DAWSON.
